STEPLADDER

Henry McAlister, Worcester, Mass.

Application April 29, 1950, Serial No. 158,945

1 Claim. (Cl. 228—17)

1

This invention relates to stepladders, and more particularly to structures of the type having a pair of steeply inclined front legs which carry a series of horizontal steps therebetween, and a pair of rear legs or other means to form a prop for the front legs.

In stepladders of this type as heretofore constructed, it has been the practice to provide rather narrow steps, usually about four inches in width. To provide wider steps, without considerable overlapping of successive steps, would require a ladder of less steepness, which would occupy much greater space, besides being very inconvenient to use in many respects. These four inch steps are much too narrow to support the feet properly, and it is very tiring to stand on such a ladder for long periods. The shins are frequently bruised by contact with the step next above the one in use. Furthermore, it is not possible to stand sidewise on these narrow steps, although it would be very convenient to do so in many instances if it were feasible.

It is accordingly one object of the invention to provide a stepladder having much wider steps than those usually employed, the construction being such that the angle of inclination of the stepladder is of the usual steepness and the full width of each step is available for use.

It is a further object of the invention to provide a relatively simple and inexpensive stepladder construction having steps which will afford firm support for the feet of a person using the same, without bruising his shins, and making it possible for him to face in any desired direction without danger of slipping or falling.

With these and other objects in view, as will be apparent to those skilled in the art, the invention resides in the combination of parts set forth in the specification and covered by the claim appended hereto.

In accordance with the invention, there is provided a stepladder having two front legs which are suitably propped to slope upwardly and rearwardly, preferably at a steep angle, these legs supporting a series of approximately horizontal steps between them. These steps are preferably spaced substantially uniformly one above the other, and they are of sufficient width (from front to rear) to afford ample support for the feet. Because of the steepness of the angle and the width of the steps, each step overlies a considerable portion, say about one-half, of the step therebeneath. Each of the steps, except the lowermost, is divided longitudinally into a front portion and a rear portion. Each of the front por-

2

tions is pivotally mounted so that it can be swung upwardly and rearwardly when desired, whereby the full width of the step therebeneath will be available for a person to stand thereon and face in any direction without interference. Preferably each front portion is hinged to the corresponding rear portion so that the front portion can be folded back to rest upon the top of the rear portion. The two front legs preferably are slightly inclined toward one another, and the ends of the front portion of each step are arranged at obtuse angles with the front edge thereof, to avoid interference with the legs during the swinging movement of the said front portion. At the upper ends of the legs there is preferably provided a horizontal top platform having a fixed rear portion and a front portion which overlaps about one-half of the upper step therebeneath, this front portion being arranged to be swung upwardly over the rear portion and to the rear thereof. Thus the full width of the upper step and of the top platform will be available for use.

Referring to the drawing illustrating one embodiment of the invention, and in which like reference numerals indicate like parts,

Fig. 1 is a perspective view of a stepladder;

Fig. 2 is a front elevation of the stepladder;

Fig. 3 is a side elevation of the stepladder;

Fig. 4 is a section taken on the line 4—4 of Fig. 2;

Fig. 5 is an enlarged section taken on the line 5—5 of Fig. 4;

Fig. 6 is a side elevation of the lower portion of the stepladder, with the front portion of the second step folded back; and

Fig. 7 is a side elevation of the upper portion of the stepladder, with the front portion of the top platform folded back.

40 The embodiment illustrated comprises a pair of front legs 10 which slope upwardly and rearwardly at a steep angle. These legs are slightly inclined toward one another, as best shown in Fig. 2. The legs 10 are considerably wider (from front to rear) than in the usual stepladder, and in order to provide the necessary strength without excessive cost or weight each leg includes a front strip 11 and a rear strip 12. These strips are substantially parallel with one another and spaced apart an appreciable distance. They are connected at their lower ends by a block 14 and at their upper ends by a horizontal cleat 15. The cleats 15 extend rearwardly behind the rear strips 12, and the rear portions of the cleats 15 are con-

nected by a horizontal rod or bolt 16 to which the upper ends of two rear legs 18 are joined. The rear legs 18 slope upwardly and forwardly at a steep angle, and they are connected to one another by a horizontal strip 19 and by a pair of crossed strips or braces 20 in known manner. Each rear leg 18 is connected to the rear strip 12 of the corresponding front leg by means of a toggle brace 22 of well-known construction. The braces 22 can be collapsed upwardly to permit the rear legs to be swung forwardly against the front legs, when the stepladder is to be stored.

Between the front legs 10 there is provided a series of horizontal steps 24, 25 and 26 located at successively higher elevations, step 24 being the lowermost. The ends of these steps are supported on horizontal cleats 28 fastened to the inner surfaces of the leg strips 11-12. The upper surface of the first step 24 is preferably about twelve inches above the floor, the second step 25 being about twelve inches above the step 24, and the third step 26 being about twelve inches above the step 25. Each of these steps preferably has a width of approximately eight inches, which is about twice the width of the steps commonly employed heretofore in stepladders of this general type. It will be noted that each of the steps 25 and 26 overlies a considerable portion (approximately one-half) of the step next therebeneath. In order that full use may be made of these wide steps, the step 25 is divided longitudinally into a front portion 30 and a rear portion 31, and the step 26 is divided longitudinally into a front portion 32 and a rear portion 33. The front and rear portions are of approximately the same width. The rear portions are suitably fixed to the cleats 28, whereas the front portions are adapted to be moved out of the way when the step therebeneath is in use. Preferably the rear edges of the front portions 30 and 32 are pivotally connected to the front edges of the corresponding rear portions 31 and 33 by means of hinges 35. Thus the front portions can be swung upwardly and rearwardly to rest on the tops of the corresponding rear portions when desired. In order that this movement can take place without interference with the inwardly inclined legs 10, the end surfaces of the front portions 30 and 32 of the steps are shaped to converge at a small angle in a forward direction, as indicated particularly at 36-36 in Fig. 4 as to the portion 30. These end surfaces are thus positioned at obtuse angles with the front edges of the steps.

At the top of the front legs 10 there is provided a top platform 38 which is supported on the cleats 15. This platform is located about twelve inches above the uppermost step 26 and overlies approximately one-half the width thereof, the platform having a width of about eight inches. As in the case of the steps 25 and 26, the platform 38 is divided longitudinally into a front portion 39 and a rear portion 40 of substantially equal widths. Small metal bars 42 are fastened to the opposite ends of the front portion 39 and extend rearwardly adjacent the end surfaces of the rear portion 40, to which the bars are pivotally attached by single screws 43 located at the centers of these end surfaces. With this construction the full width of the uppermost step 26 can be made available by swinging the front portion 39 of the platform 38 upwardly and rearwardly to a position directly behind the rear portion 40, as shown in Fig. 7. Whether the portion 39 be positioned in front of the portion 40 or behind the same, the

platform 38 will still have the same effective width.

It will now be apparent that with the construction as disclosed a workman may stand comfortably and safely on any one of the wide steps or the top platform. His feet will be firmly supported, he will not bruise his shins, and he can face in any desired direction, with his two feet positioned side by side on the step or platform. If he wishes to stand on the lowermost step 24, he need merely fold back the front portion 30 of the second step 25, as shown in Fig. 6. If he wishes to stand on the second step 25, he will leave it in its full width position and fold back the front portion 32 of the third step 26. If he wishes to stand on the third step 26, he will leave it in its full width position and fold back the front portion 39 of the top platform 38, as shown in Fig. 7. He may stand on the top platform 38 with the parts in either of the positions shown in Fig. 3 or 7. When he is standing on one of the steps he may use the top platform to support a pail, tools or the like.

It will be recognized that the invention provides a stepladder which is much safer and more comfortable to use than prior constructions. It is simple and inexpensive to manufacture, and it can be made with as steep an inclination as the usual stepladder, so that it can be used in a restricted space.

Having thus described my invention, what I claim as new and desire to secure by Letters Patent is:

A stepladder comprising a pair of laterally spaced front legs, prop means to support the legs at an upward and rearward inclination, the legs being slightly inclined toward one another, a series of steps located between the legs, the steps being relatively wide so that each step overlies a considerable portion of the step therebeneath, each step except the lowermost being divided longitudinally into a rear portion and a front portion, hinge means pivotally connecting each of said front portions to the corresponding rear portion so that the front portion can be swung upwardly and rearwardly to rest on the top of the corresponding rear portion to make substantially the full width of the step therebeneath available for use, the end surfaces of the hinged front portions of the steps converging in a forward direction at a sufficient angle to avoid interference with the legs as the front portions are swung upwardly and rearwardly, a top platform at the top of the legs overlying a considerable portion of the top step therebeneath, the said platform being divided longitudinally into a rear portion and a front portion, and means pivotally connecting the front portion of the platform to the rear portion thereof and so constructed that the front portion can be swung upwardly and rearwardly into a position behind the rear portion and thereby make substantially the full width of the top step available for use while retaining the full width of the platform.

HENRY McALISTER.
